Charles O. Bailar, Menasha, Wis., assignor to
Marathon Corporation, a corporation of Wisconsin

Application July 21, 1944, Serial No. 545,923

1 Claim. (Cl. 229—30)

This invention relates to a tray for supporting articles. More specifically, this invention relates to supporting a tray made from a single blank of cardboard and the like that can be shipped in flat collapsed condition and which is adapted to be readily set up for use.

Further advantages and features of the invention will be apparent from the following specification and drawings, wherein,

Figure 1 is a perspective view of a package of bakery rolls supported on a tray made according to the present invention and completely wrapped in a transparent wrapper,

Figure 2 is a plan view of the package illustrated in Figure 1,

Figure 3 is a sectional view taken on lines 3—3 of Figure 2,

Figure 4 is a plan view of an elongated cardboard blank from which the tray of the present invention is constructed,

Figure 5 is a perspective view of the tray in set-up condition, and

Figure 6 is a plan view of the flat collapsed tray as shipped to the user.

Referring to the drawings, the tray is preferably made from an elongated relatively narrow blank of cardboard of suitable caliper, as illustrated in Figure 4, which is scored along lines 1, 2, 3, and 4 to provide opposed end walls 10 and 12, opposed side walls 11 and 13, and a glue panel 14. Side walls 11 and 13 are provided with article supporting panels 16 which are formed by a slit or cut line 5 extending in parallel relation to the bottom edge of the panels 11 and 13, and slit or cut lines 8 intersecting the cut lines 5 at each end thereof and terminating at the ends of hinge line formed of alternate creased score lines 6 and cut score lines 7.

In forming the tray from the blank described previously, glue panel 14 is folded along score line 4 into face contact with panel 13. Adhesive is then applied to the margin 15 of panel 10. The blank is then folded back on itself along score line 3 as illustrated in Figure 6, so as to bring glue panel into contact with adhesive 15 on panel 10 thereby forming a rectangular sleeve. The sleeve so formed is shipped in this flat condition to the consumer.

In use, the flat collapsed tray illustrated in Figure 6 is opened up and folded along score lines 1, 2, 3 and 4 so as to bring the end walls 10 and 12, and side walls 11 and 13 in opposed

condition as illustrated in Figure 5. The article supporting panels 16 are then folded inwardly of the tray toward each other on their hinge lines to assume the position illustrated in Figures 3 and 5. In this position any suitable articles, such as bakery rolls 30, can be positioned and supported on the extended supporting panels 16. It will be noted as shown in Figure 3 that the outer free edges of panels 16 terminate short of each other so as to permit air to circulate beneath the articles supported by panels 30. The rectangular openings in the side walls 11 and 13, formed by folding panels 16 inwardly also serve to permit air circulation about the sides of the articles supported in the tray. This is an important feature of the present invention when bakery goods such as rolls, doughnuts and cakes are packaged in the tray in order to prevent them from becoming soggy. A transparent wrapper 20 of Cellophane and the like is preferably wrapped around the package in order to protect the contents against contamination. If desired, an identification band 40 having suitable printed indicia thereon may be placed around the package, preferably within the outer transparent wrapper.

The present invention may be embodied in other specific forms without departing from the spirit or essential attributes thereof, and it is therefore desired that the present embodiment be considered in all respects as illustrative and not restrictive, reference being had to the appended claim rather than to the foregoing description to indicate the scope of the invention.

35 I claim:

A tray for supporting articles formed of an elongated integral blank, the ends of said blank being partially overlapped and fastened together to form a rectangular band, said blank being provided with score lines to form opposed end walls and elongated side walls, said side walls being provided with panel portions folded inwardly toward each other on a hinge line extending in parallel relation to the bottom edge of said side walls, said panel portions being formed by a cut line extending in spaced parallel relation to the said hinge line and cut lines extending downwardly from the ends of said cut line at right angles thereto and terminating at the said hinge line, said panel portions being adapted to assume a position for supporting articles thereon.

CHARLES O. BAILAR.
